UNITED STATES PATENT OFFICE.

FRANK F. SLOCOMBE, OF PHILADELPHIA, PENNSYLVANIA.

LEATHER-FINISHING MACHINE.

1,199,122.

Specification of Letters Patent. Patented Sept. 26, 1916.

Application filed October 29, 1913. Serial No. 797,967.

To all whom it may concern:

Be it known that I, FRANK F. SLOCOMBE, a citizen of the United States, residing in the city and county of Philadelphia, State of Pennsylvania, have invented a new and useful Leather-Finishing Machine, of which the following is a specification.

My present invention consists of a novel leather finishing machine wherein novel means are provided for preventing the turning over of the leather by the brush rolls as it passes between such brush rolls and the surface of the drum.

It further consists of means for adjusting the position of such means with relation to the brush rolls and the leather to be treated.

It further consists of a novel leather finishing machine wherein is employed a plurality of brush rolls and in conjunction therewith holding devices are provided extending into the brushes of said rolls and arranged at varying positions on the different rolls, so that the impression left on the skin by the holding devices of one roll will not be coincident with the impression left on the skin by the holding devices of another roll.

In a prior patent granted to me and William E. Poinsett, on August 10th, 1909, No. 930,700, we have shown and broadly claimed novel means for preventing the turning over of the leather by the brush rolls, and my present invention while coming within the broad and generic scope of the patent above referred to, is directed to a somewhat different construction from that shown in said patent.

It further consists of other novel features of construction, all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise

arrangement and organization of these instrumentalities as herein shown and described.

Figure 1 represents a sectional elevation 55 of a leather finishing machine embodying my invention. Fig. 2 represents a top plan view thereof. Fig. 3 represents a plan view of the leather retaining means in detached position. Fig. 4 represents a sectional view 60 of the leather holding device. Fig. 5 represents a sectional view of a portion of the machine showing more clearly the manner of adjusting the container for the finishing material. Fig. 6 represents a side elevation 65 of a portion of the machine showing more clearly certain details of construction.

Similar numerals of reference indicate corresponding parts in the figures.

Referring to the drawings, 1 designates 70 the frame of the machine in which is mounted a driving shaft 2 provided with pulleys 3 and 4 thereon, one of which is loose and the other fixed with respect to said driving shaft. The driving shaft 2 has fixed thereon a pinion 5 which meshes with a gear 6 mounted on a shaft 7 suitably journaled in the machine frame. The shaft 7 has fixedly secured thereto a pinion 8 which meshes with a gear 9 mounted on a shaft 10 journaled in 80 the frame 1. The shaft 10 has fixedly mounted thereon a drum 55 which serves as a support for the leather or skin which is to be treated. The shaft 2 is provided with a pulley 11 around which passes a belt 12 85 which latter also passes around a pulley 13, which latter is mounted on a shaft 14 journaled in the machine frame. The shaft 14 carries a brush 15 which is adapted to revolve within a container 16 for the finishing 90 material. The position of the container 16 with respect to the brush 15 may be varied by means of the adjusting screws 17 which are in threaded engagement with the container, as seen at 56, Fig. 5, it being understood that the longitudinal movement of the adjusting screws 17 is prevented by means of the set collar 57.

18 designates a transfer roll or brush mounted in journal bearings 19, the boxes of 100 which are guided in the slots 20 and provided with adjusting screws 21.

- 22 designates a brush roll mounted in journal bearings 23 the boxes of which are guided in slots 24 and provided with adjusting screws 25.
- 26 designates a brush roll mounted in journal bearings 27 the boxes of which are guided in slots 28 and provided with adjusting screws 29.
- 30 designates a brush roll mounted in journal bearings 31, the boxes of which are guided in the slots 32 and provided with adjusting screws 33.
- The shaft 14 of the brush 15 has fixed thereon a gear 34 which meshes with a gear 35 on the shaft of the transfer roll 18. The gear 35 meshes with a gear 36 on the shaft of the brush roll 22. The shaft 14 is also provided with a pulley 38, see Fig. 2, around which passes a belt 39 which latter also passes around a pulley 40 on the shaft of the brush roll 26. 41 designates a belt which also passes around the pulley 40 and around a pulley 42 on the shaft of the brush roll 30.
- 25 It will be understood that by means of the connections hereinbefore described the different rolls and the drum are revolved in the directions indicated by the arrows in Fig. 1.
- 30 Referring now to the novel means employed for preventing the turning over of the leather during the finishing operation, it will be seen that the same comprises a bar or frame 43 to which are secured the members 44 in a manner best illustrated in Fig. 4. The members or bars 44 have their inner ends deflected upwardly and laterally so as to pass through apertures in the bar 43 and be fixed in assembled position with respect thereto by means of the fastening devices 45, illustrated as consisting of screws. The members 44 consist of bars or rods shaped to conform to the operative surface of the leather support and since such support has been illustrated as consisting of a drum, said members 44 are slightly curved and the outer ends are preferably upwardly or outwardly deflected. The ends of the bar 43 are connected with supporting arms 46 which are secured thereto by means of fastening devices 47 consisting, in the present instance, of washers and of nuts in threaded engagement with the ends of the bars or threaded rods connected therewith.
- 50 The free ends of the supporting arms 46 are rearwardly deflected to form slots 48, see Fig. 1, whereby the leather holding devices may be adjusted in a radial or other direction with respect to the drum 55 or the brush roll.
- I preferably employ a leather holding device to operate in conjunction with each brush roll, such as 22, 26 and 30, and secure such devices in position by means of bolts 49 carried by the frame 1 and passing

through the slots 48, said bolts being provided with nuts 50 whereby the leather holding devices are maintained in their adjusted position.

51 designates a table carried by a bracket 70 52 and terminating in proximity to the drum 55.

A drip-tank 53 is preferably provided and supported in any desired manner, said tank being provided with a discharge conduit 54 75 55 leading to a desired point of utilization.

In the operation, the driving shaft 2 is driven by any desired source of motive power whereupon, as is evident, the drum 55 and the different rolls will be actuated in 80 the directions of the arrows seen in Fig. 1. The leather or skin 58 to be treated is fed from the table 51 on to the leather support 55 which, in the present instance, is the revolving drum, and passes beneath the brush 85 rolls 22, 26 and 30 so that the leather finishing material which is fed to the skins from the container 16 by means of the brush 15, transfer roll 18 and brush roll 22 is worked into the leather or skin in a very efficient 90 manner.

The members 44 of the leather holding devices pass into the brushes of the brush rolls 22, 26 and 30 to any desired extent and if desired they may pass through and beyond the brushes, as seen in Fig. 1. These members 44 of the different sets are arranged in staggered relation so that the impression left on the skin caused by the divergence of the bristles of the holding devices 100 on one roll are not coincident with the mark or impression on the skin caused by the divergence of the bristles on the next roll. In the present instance, I have preferred to show these members 44 as located a slight 105 distance above the leather being treated so that they are normally out of contact therewith but such devices are adjusted in such a manner that they positively prevent any turning over of the leather during the 110 brushing operation.

The container 16 for the leather finishing material may be readily adjusted with respect to the brush 15 by actuating the set screws 17. The transfer roll may be adjusted with respect to the parts co-operating therewith by adjusting the set screws 21. The brush rolls 22, 26 and 30 may be readily adjusted with respect to the leather supporting drum 55 by actuating the set screws 120 25, 29 and 33 respectively, as will be apparent to those skilled in this art.

For the purpose of illustrating one manner of carrying out my invention in practice, I have shown the members 44 of a 125 leather holding device as arranged substantially parallel with each other.

It will be apparent from the construction seen in Fig. 6, which is an end view of the upper portion of one side of the machine, 130

that I have provided a convenient and readily manipulated adjusting means whereby the brushes can be readily moved toward or away from the material to be treated, it being of course understood that the construction seen in Fig. 6 is employed upon both ends of the bearings for the brush rolls. I have deemed it unnecessary to show a detailed view of each end of the machine, since it is thought that the construction and arrangement of the power transmission devices shown in Figs. 1 and 2 will be clearly apparent to those skilled in the art and it will furthermore be apparent that I may employ other means than that shown for the purpose of rotating the drum 55 and the various other operative parts of the machine, such as the brush rolls 15, 18, 22, 26 and 30. It will furthermore be apparent that I can employ other means for supporting and adjusting the fingers or members 44 and that the same may be attached to their supports as the bar 43 by other devices than that shown. It will furthermore be apparent that while my invention is particularly designed for the treatment of skins or leather, it may be employed with equal facility in the treatment, coating or finishing of other articles than skins or leather, as will be apparent to those skilled in the art.

I desire to call special attention to the advantages attained for the employment of the laterally extending members or fingers 44 which are arranged in such relation to each other and to the brush rolls that there will be no streaks or marks left upon the article which is being treated or finished after its delivery from the machine. As a result of the arrangement and collocation of the guide members or fingers 44 in staggered order, every portion of the article to be treated will be retained in the desired position with respect to the drum and the rolls during the finishing operation, as is evident.

It will now be apparent that I have devised a novel and useful construction of a leather finishing machine which embodies the features of advantage enumerated as desirable in the statement of the invention and the above description, and while I have, in the present instance, shown and described a preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a leather finishing machine, a support for the leather to be treated, a brush roll mounted to revolve in proximity to said support, means to revolve said roll, and hold-

ing devices arranged substantially parallel to each other and having free ends extending into the brushes of the brush roll.

2. In a leather finishing machine, a support for the leather, a rotatable brush roll, means to revolve said roll, holding devices arranged substantially parallel to each other and having free ends extending into the brushes of the brush roll, and means to adjust said holding devices with respect to the periphery of the brush roll.

3. In a leather finishing machine, a support for the leather, a rotatable brush roll, means to revolve said roll, and holding devices arranged substantially parallel to each other and having free ends extending into the brushes of the brush roll, and arranged substantially parallel to the operating surface of said support.

4. In a leather finishing machine, a support for the leather, a rotatable brush roll, means to revolve said roll, and holding devices arranged substantially parallel to each other and having free ends extending through the brushes of the brush roll.

5. In a leather treating machine, a support for the leather, a rotatable brush roll, means to revolve said roll, and holding devices having free ends extending into the brushes of the brush roll and normally out of contact with the leather being treated but adapted to engage therewith to prevent buckling or turning over of the leather by the brushes.

6. In a leather finishing machine, a support for the leather, a rotatable brush roll, means to revolve said roll, and holding devices arranged substantially parallel to each other and having free ends extending into the brushes of said roll, and means for adjusting the distance or amount of contact between said brush roll and said support for the leather.

7. In a leather finishing machine, a support for the leather, a plurality of rotatable brush rolls, means to revolve said rolls, holding devices having free ends extending into the brushes of said rolls, said holding devices being arranged at varying positions on one roll from those on the next succeeding roll, so that the mark or impression left on the skin by the divergence of the bristles caused by the holding devices on one roll shall not be coincident with the mark or impression caused by the divergence of the bristles on the next roll.

8. In a leather finishing machine, a support for the leather to be treated, a brush-roll mounted to revolve in proximity to said support, a bar supported parallel to said support and brush-roll, and holding rods supported to project from said bar and having their free ends extending into the brushes of the brush-roll.

9. In a leather finishing machine, a sup-

port for the leather to be treated, a brush-roll mounted to revolve in proximity to said support, a bar supported parallel to said support and brush-roll, holding rods supported to project from said bar and having their free ends extending into the brushes of the brush-roll, and means for adjusting said bar in its relation to said support and brush-roll.

10 10. In a leather finishing machine, a rotating supporting roller for the leather to be treated, a rotating brush-roll journaled par-

allel and in proximity to said supporting roller, a bar supported parallel to said supporting roller and brush-roll, and holding rods supported to project from said bar to extend into the brushes of the brush-roll and having their free outer portions curved to conform to the curvature of the supporting roller.

FRANK F. SLOCOMB.
